UNITED STATES PATENT OFFICE.

FREDERICK H. RENARD, OF WILKESBARRE, PENNSYLVANIA.

APPARATUS FOR REMOVING ELECTRIC-LIGHT BULBS.

SPECIFICATION forming part of Letters Patent No. 675,640, dated June 4, 1901.

Application filed January 2, 1901. Serial No. 41,860. (No model.)

To all whom it may concern:

Be it known that I, FREDERICK H. RENARD, a citizen of the United States, residing at Wilkesbarre, in the county of Luzerne and State of Pennsylvania, have invented certain new and useful Improvements in Apparatus for Removing Electric-Light Bulbs; and I do hereby declare the following to be a full, clear, and exact description of the invention, such as will enable others skilled in the art to which it appertains to make and use the same.

My invention relates to improvements in apparatus for removing electric-light bulbs; and it consists in a pole or handle portion, an arm adjustably secured thereto, gearing carried by the said arm, means for grasping the bulb of an incandescent electric light, and means for rotating the said gearing, whereby the bulb may be unscrewed from its socket or screwed into the same.

It further consists in certain other novel constructions, combinations, and arrangements of parts, as will be hereinafter fully described and claimed.

In the accompanying drawings, Figure 1 is a side elevation of my improved apparatus for removing or replacing electric-light bulbs, a portion of the same being broken away. Fig. 2 is a detail side elevation of the upper end of said apparatus, the parts being adjusted to grip a bulb arranged at a different angle from the one gripped by the device shown in Fig. 1. Fig. 3 is a detail side elevation of the handle or pole with its telescoping sections arranged within one another. Fig. 4 is a detail view of an adjusting-plate for regulating the tension of the cable or rope employed in operating the gearing of the said apparatus. Fig. 5 is a detail sectional view through a dummy bulb and a portion of a lamp-socket, showing the means of removing a lamp where the globe or bulb has been broken. Fig. 6 is an enlarged detail view showing the snap-hook connection between sections of the operating cable or belt.

In the use of electric lights, particularly the incandescent bulb lights, the said bulbs are arranged in very many different positions and at such different heights that it is often very difficult to reach or get at bulbs which have been burned out or broken or which need replacing for any reason. I have devised the

plan of using a pole or handle of suitable length provided with means by which a bulb may be grasped, no matter what the position or angle of the said bulb, and may be unscrewed and a new one inserted in its place.

In embodying my invention in a practical form I employ a suitable handle, as 1, to the upper end of which is adjustably secured an arm 2, which is preferably formed with its outer end 3 bent at right angles to main stem thereof. The handle 1 when the lights to be reached are only at a moderate height may be formed of an ordinary bamboo pole or similar material; but I preferably make the said handle of a series of telescoping sections, as 4 4, by which the handle may be altered in length to suit the height or position of the different bulbs to be operated upon. As shown in Fig. 3 of the drawings, the sections 4 4 are made of hollow tubing of successively-smaller diameters, so that all of the upper sections may be made to telescope within the lower section, and means, such as set-screws 5 5, may be employed for holding the sections in different adjusted positions and to prevent their slipping. The lower end of each pole-section is slightly larger than the top of the next section below, so that the joints may be made rigid when the pole is extended. The inner end of the lower section 4 is preferably provided with an inwardly-extending cone, as 6, adapted to engage the inner ends of the telescoping sections and prevent them from dropping too far within each other and within the outer section. This cone engages the different-sized bores of the said sections, and thereby spaces them properly with respect to each other. Each section 4 is provided with one or more projections, as 7 7, having guiding eyes or loops 8 formed at their outer ends, adapted to receive and direct the movement of an operating belt or cable 9, as will be hereinafter described.

The arm 2 carries at its outer end an adjustable arm 10, which is pivoted to the bent end 3 of the said arm 2 and is adapted to be adjusted at different angles with respect to the same by means of a set or clamp screw 11, passing through the pivotal points of the said arms. A portion of the arm 10 is bifurcated, as at 12, so that the said arm may inclose the bent end portion 3 of the arm 2.

The arm 10 is also provided with a bent end 13, so that by the adjustment of the arm 10 upon its pivotal point the end 13 thereof may be made to coincide with the axis of the handle 1 or may be folded into a position to one side of but parallel therewith, as seen in Fig. 2. The parts may also be moved to intermediate positions for adjusting the end 13 of the arm 10 at any desired angle. The end 13 of the arm 10 carries a beveled gear-wheel, as 14, which meshes with a beveled gear 15, also pivotally secured upon the end of the arm 13. Into the outer face of the gear 15 are set a series of curved arms 16 16, preferably four 15 in number, which arms are flexible or are adapted to spring apart, so that they may be forced upon the globe of an electric-light lamp. The rods 16 16 are covered for a greater portion of their length with tubular 20 pieces of rubber, as 17 17, so that the said rods will be adapted to more firmly grasp the electric-light bulbs. The outer ends of the rods 16 are preferably curved outwardly, as at 18, so as to be forced upon the said bulbs 25 easily. By engaging a bulb with the rods or arms 16 and rotating the gearing carrying the said arms the bulb may be unscrewed from its socket or screwed into the same, as desired.

30 In order to actuate the gearing 14 and 15, I preferably form upon the gear-wheel 14 an adjustable pulley, as 19, which is grooved and adapted to engage one or more belts, as 9. The lower portions of the belt extend downwardly along the handle 1 and engage a groove formed in an operating pulley or wheel, as 20, which is secured to the lower end of the handle. The belt or cable 9 after passing around the pulley 19 extends through the guiding-35 eyes 8 8 of the handle-sections and thence 40 around the actuating-pulley 20. The guiding-eyes 8 8 serve to hold the belt 9 in position no matter to what angle the arm 10 is turned. The use of these eyes will be well 45 understood by reference to Fig. 2 of the drawings. While I may employ more than one belt 9, I preferably use one, as seen in Fig. 1 of the drawings, one end of the belt 9 engaging one groove upon the pulleys 19 and 20, while 50 the other engages another groove. Each end of the belt is firmly secured to the pulley by a suitable means, a convenient way being to pass the ends of said belt through an aperture in the periphery of the pulley, as at 19^a, knotting the said ends to hold them. The 55 ends of the belt are then given several turns around the pulley 19, each in its own groove. Of course I may use a greater number of belts without departing from the spirit of the invention. The belt 9 is preferably formed in 60 sections and is provided at its ends with snap-hooks, as 21 21, of any suitable construction, so that the length of the belts may be altered to suit the length of the handle 1. The belts 65 may be made taut by adjusting the pulley 20 with respect to the pulley 19, and for this purpose I preferably mount the pulley 20 upon

an adjusting bar or plate 22, which is formed with a series of apertures 23, adapted to engage a hook or projection 24, secured to the 70 lowest handle-section 4. The plate 22 also passes through a guide-clip, as 25, secured to the handle 1 for properly holding it in position. The pulley 20 is pivoted to the upper end of the bar 22.

75 When it is desired to tighten the belt, the plate 22 is moved downwardly and the proper aperture is brought into engagement with the hook 24 for securing the said plate in its adjusted position. Any degree of tightness may 80 thus be secured in the belt or cable. By means of this adjustment the belt can be kept sufficiently tight to prevent its slipping upon the pulleys when operating the gearing.

It very often happens that the glass bulbs 85 of incandescent lights become broken, and in such event the arm 16 could not be well employed for unscrewing the broken lamp. In order to be able to use the apparatus, however, under these conditions, I provide a 90 dummy bulb, as 26, which may be made of wood or any suitable substance and is provided in its end with a recess or socket 27, adapted to fit upon the usual glass shank 28, which is employed in bulb-lamps for holding 95 the carbon filaments in position. Such glass shanks are usually flat in contour, so that by inclosing the same within the recess 27 of the dummy bulb 26 the lamp may be unscrewed, as desired. The bulb 26 fits within the arm 16 in the same manner as the glass bulb of a perfect lamp would. By the use of guiding-100 eyes 8 it does not matter at what angle the arm 10 is turned in order to engage any lamp, since the said eyes will hold the belt tight 105 against the pulley 19 in any of the adjusted positions of the arm 10. By using a clamp-screw 11 at the pivoted connection between the arm 2 and the arm 10 the angle to which the device is adjusted with respect to the 110 handle can be quickly altered and firmly clamped.

In using the apparatus the handle is adjusted to the length necessary for reaching the lamp to be unscrewed. The fingers or arms 115 16 are then forced upon the glass bulb of the lamp and the pulley 20 is rotated, preferably by means of a crank-handle 29, secured thereto, and thus through the agency of the belt or cable 9 will revolve the pulley 19, actuating the gears 14 and 15 and rotating the arms 16 and the lamp grasped within the same.

The curved arms 16 16 may be constructed of different sizes to adapt them for gripping bulbs of different sizes. They may be riveted in position in the gear 15, in which case the gear-wheel will be removed when it is desired to use arms for a different-sized bulb, and another gear having the arms of the desired shape and size can be substituted. The 125 arms themselves, however, may be removably secured to the gear 15, as by screwing them in place, so that the gear need not be removed when changing the arms. In the 130

place of arms I also contemplate employing a suitably-shaped rubber cup, which may be secured to the gear for grasping the bulb of the lamp to be operated upon.

5. The operation of the device is exceedingly simple, and its adjustment can be readily effected to suit every circumstance.

It is sometimes well to inclose the pulley 19 in a casing, as 30. (Shown in Fig. 2 of the drawings.) When such a casing is used, there is less danger of the belts becoming disengaged from the groove in the periphery of the pulley, especially when the length of the handle is being altered and the length of the 15 belt is being changed.

Having now described my invention, what I claim as new, and desire to secure by Letters Patent, is—

1. An apparatus for screwing or unscrewing 20 electric-light bulbs, comprising a handle, intermeshing gears mounted on said handle, bulb-engaging means carried by one of said gears, a drum or pulley carried by the other gear, and means for rotating said drum for 25 communicating motion to the bulb-engaging means, substantially as described.

2. An apparatus for removing or replacing 30 bulb-lamps, comprising a handle formed of a series of telescoping sections, means for adjusting the said sections to lengthen or shorten the handle, gearing carried by the said handle comprising a bulb-holding gear and a gear formed with an actuating-drum thereon, and means for rotating the drum and thereby the 35 gearing, substantially as described.

3. An apparatus for removing or replacing 40 bulb-lamps, comprising a handle, a removable arm secured thereto, an adjustable arm carried by said removable arm, means for holding the latter arm at various angles with 45 respect to the handle, gearing carried by the said adjustable arm, and bulb-engaging means secured to the said gearing whereby upon rotating the gearing the bulb may be turned for removing or replacing it, substantially as described.

4. In an apparatus for removing or replacing 50 bulb-lamps, a handle provided with an end portion bent at an angle to the said handle, an angular arm pivoted to said bent end and adapted to fold upon the same, a gear-wheel carried by the said arm, a second gear-wheel carried by the said arm and meshing therewith, bulb-gripping means carried by 55 the second gear-wheel, and means for turning the first gear-wheel, whereby the second one will be actuated for screwing or unscrewing the lamp, substantially as described.

5. An apparatus for removing or replacing 60 lamp-bulbs, comprising a handle made up of telescoping sections, guiding-eyes secured to the sections of the said handle, gearing mounted upon the handle, belts for operating the said gearing, said belts passing through 65 the guiding-eyes, means for securing the gearing at different angles to the handle, the guiding-eyes holding the belts in proper re-

lation thereto, and bulb-gripping means operated by the said gearing, substantially as described.

6. An apparatus for removing or replacing 70 bulb-lamps, comprising a handle made up of a series of telescoping sections, means in the outer section for spacing the other sections when the handle is in its shortest form, comprising a cone extending into the outer section and adapted to engage the ends of the inner sections, gearing carried by the said handle, and bulb-grasping means operated by the said gearing, substantially as described. 80

7. An apparatus for removing or replacing 85 bulb-lamps, comprising a handle formed of a series of telescoping sections, guiding-eyes secured to each section, gearing carried by the said handle, belts for operating the said gearing, said belts passing through the said guiding-eyes, whereby the belts will be held in proper position with respect to the handle, and bulb-grasping means operated by the 90 said gearing, substantially as described.

8. An apparatus for removing or replacing 95 bulb-lamps, comprising a handle formed of extensible sections, gearing carried by the said handle, belts for operating the said gearing, pulleys at each end of the said handle 100 for receiving the belts, the said belts being formed of detachable sections, means for connecting them together at their ends, the structure being such that the length of the belts may be adjusted to correspond with the 100 length of the handle, and bulb-grasping means operated by the said gearing, substantially as described.

9. An apparatus for removing or replacing 105 bulb-lamps, comprising a handle, a removable arm secured in the upper end thereof having an end portion bent at right angles to the main stem, an angular arm pivoted to the outer end of the said bent portion, a portion of the said angular arm being bifurcated 110 to fit upon the bent end portion of the said stem, a set or clamp screw for clamping the angular arm in different positions upon the handle, intermeshing gears carried by the said bent arm, and bulb-engaging means carried by one of the said gears, whereby upon 115 rotating the gearing the bulb may be revolved, substantially as described.

10. An apparatus for removing or replacing 120 bulb-lamps, comprising a handle, gearing mounted near one end thereof, bulb-engaging means carried by one gear, a pulley or drum mounted on the other gear, an actuating pulley or drum on the handle near its lower end, belts connecting the actuating 125 pulley with the gear-pulley, the structure being such that by turning the actuating-pulley the bulb may be revolved through the agency of the pulleys and the said gearing, substantially as described.

11. An apparatus for removing or replacing 130 bulb-lamps, comprising a handle, gearing carried near one end thereof, bulb-engaging means operated by the said gearing, a pulley

secured to one of the gears of said gearing, an actuating-pulley secured to the handle, belts connecting the two pulleys, an adjusting-plate interposed between the said pulley and the said handle, said plate having a series of apertures formed thereon adapted to be brought into engagement with a projection or hook on the handle, and a guiding-clip for holding the plate in position, the structure being such that by adjusting the said plate the belts connecting the pulleys may be made taut so as not to slip, substantially as described.

12. An apparatus for replacing or removing lamp-bulbs, comprising a handle, gearing mounted thereon, a bulb-grasping device com-

prising flexible arms, a dummy bulb adapted to fit therein and provided with a recess in its end for engaging the glass shank of a broken lamp, the structure being such that by inserting the bulb in the grasping-arms and bringing the recess therein in engagement with the glass shank of the broken lamp, the same may be revolved for unscrewing it, substantially as described. 25

In testimony whereof I hereunto affix my signature in presence of two witnesses.

FREDERICK H. RENARD.
